US00D768594S

(12) **United States Design Patent** (10) **Patent No.:** **US D768,594 S**
(45) **Date of Patent:** **** Oct. 11, 2016**

(54) **ELECTRONIC DEVICE**

(71) Applicant: **NANOPOINT TECHNOLOGY INC.**,
Markham (CA)

(72) Inventor: **Timothy Jing Yin Szeto**, Markham
(CA)

(73) Assignee: **NANOPOINT TECHNOLOGY INC.**,
Markham (CA)

(**) Term: **14 Years**

(21) Appl. No.: **29/504,009**

(22) Filed: **Oct. 1, 2014**

(51) **LOC (10) Cl.** **14-03**

(52) **U.S. Cl.**
USPC ..... **D14/138 G**

(57) **CLAIM**

The ornamental design for an electronic device, as shown and described.

DESCRIPTION

FIG. 1 is top front perspective view of an electronic device showing my new design;

FIG. 2 is a bottom rear perspective view thereof;

FIG. 3 is front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top front perspective view thereof showing on screen environment in a state of operation;

FIG. 10 is a bottom rear perspective view thereof showing on screen environment in a state of operation;

FIG. 11 is front view thereof showing on screen environment in a state of operation;

FIG. 12 is a right side view thereof showing on screen environment in a state of operation; and,

FIG. 13 is a left side view thereof showing on screen environment in a state of operation.

The broken lines present both in FIGS. 1 to 8 and corresponding ones of FIGS. 9 to 13 represent the bounds of the claimed design. The additional broken lines in FIGS. 9 to 13 show on screen environment in a state of operation. The broken lines form no part of the claimed design.

1 Claim, 10 Drawing Sheets
